UNITED STATES PATENT OFFICE

2,041,531

APPARATUS FOR MAKING SHOE SOLES

William J. De Witt and Erle Floyd Beers, Auburn,
N. Y., assignors to Dun Deer Sandals, Inc.,
Auburn, N. Y., a corporation of Delaware

Original application April 10, 1933, Serial No.
665,296. Divided and this application May 25,
1935, Serial No. 23,391

8 Claims. (Cl. 12—27)

This invention relates to an improvement in apparatus for making shoe soles being a further development of the invention disclosed in Patent No. 1,843,753, dated February 2, 1932 and has for its primary object to provide a machine for splitting the edges of shoe soles, one of the steps in the preparation of such soles for the assembly of shoe uppers therewith. The present application is a division of our copending application

10 Serial No. 665,296, filed April 10, 1933.

In the drawing:

Fig. 1 is a side elevation of one form of machine embodying the present invention;

Fig. 2 is a plan view thereof;

15 Fig. 3 is an enlarged sectional view illustrating the sole splitting tool and associated elements in operation; and

Fig. 4 is a plan view of the tool surrounding ring.

20 The sole having been blanked in any well known manner as for example by the use of the machine disclosed in either the above mentioned patent or application is further prepared for assembly by splitting the edge upon the machine 25 80 shown in the drawing.

The machine 80 comprises a U-shaped frame 81 through the legs 82 of which extends a shaft 83 driven by a pulley 84. Collars 85 and 86 on the shaft permit its adjustment vertically in the frame. Fixed at the upper end of the shaft 83 in any desired manner is a rotatable cutting knife 87 by which the splitting operation is performed. Mounted on the frame 81 is a bed plate 88 having a central opening 89 through which the knife 87 projects above the bed plate. Supported on the annular flange 90 of the bed plate which defines the opening 89 is a ring 91 provided at its inner periphery with a depression concave in cross section as shown in Fig. 3. The depression has two portions 92, 93 substantially the same in extent. The portion 92 is more sharply inclined and terminates in a line nearer the knife than the line in which the portion 93 terminates (see Fig. 4). Mounted upon a post 95 carried by the frame 81 is a guard plate 96 having an opening therein above the knife 87. The guard plate 96 is yieldably depressed by a spring 97 which surrounds a threaded stud 98 and is held against the plate by a knurled nut 99. An adjustable set

50 screw 100 threaded in the bed plate bears against the guard plate 96 and thus limits the upward movement of the guard plate. Fixed above the cutting knife 87 are two washers 101 the lower of which acts as a stop to determine the depth

5 in the description of the splitting operation hereinbelow. A sleeve 102 lines the opening 89 and the top surface of the upper leg 82 of the frame is cut away to form a pocket 103 which receives the collar 85 and into which the dust and fibres, made by the splitting, fall. Bushings 104 position the shaft 83 and against them bear the collars 85, 86.

As shown in Fig. 3 the sole 105 to be split is turned over and pushed below the guard plate 96 onto the knife until the under lip 106 bears against the washer 101. The sole is then rotated in the direction of the rotation of the cutting knife (indicated by an arrow in Fig. 4) until the edge of the sole has been split either entirely or as much as desired. The sole extends over the portion 92 of the depression in the ring 91 at the beginning of the splitting operation but, as the cutter enters, the sole is swung so that the completely slotted area is over the portion 93 of the depression to allow the upper lip 107 to swing away freely from the lip 106 and prevent the catching and possible severing of that lip between the knife 87 and the edge of the depression 92.

25 While one embodiment of our invention has been shown and described it will be understood that we are not limited thereto and that other embodiments may be made without departing from the spirit and scope of the invention as set forth in the following claims.

We claim:

1. A machine for splitting the edge of a shoe sole along a line intermediate the upper and lower surfaces of the sole to form upper and lower lips, comprising a rotatable cutting knife, a washer adjacent one face of the knife and against which one lip of the sole bears to determine the depth of the split, and a ring adjacent the other face of the knife and having a depression therein into which enters the other lip of the sole as it is being formed, the depression being circular and made in two portions each of which is bounded in part along an arcuate line, the line of one portion being nearer the knife than that of the other portion, the sole extending into contact with the blade at the beginning of the splitting operation past the first named portion and thereafter past the second named portion.

2. A machine for splitting the edge of a shoe sole along a line intermediate the upper and lower surfaces of the sole to form upper and lower lips, comprising a bed plate, a rotatable cutting knife adjacent the upper surface thereof, a wash-

50

55

er adjacent the upper face of the knife against which the lower lip of the sole bears to determine the depth of the split and a ring carried by the bed plate below the other face of the knife and 5 having a depression therein into which enters the upper lip of the sole as it is formed.

3. A machine for splitting the edge of a shoe sole along a line intermediate the upper and lower surfaces of the sole to form upper and lower lips, 10 comprising a rotatable cutting knife, a washer adjacent the upper face of the knife against which the lower lip of the sole bears to determine the depth of the split and a ring below the other face of the knife and having a depression therein into 15 which enters the upper lip of the sole as it is formed, the depression being circular and made in two portions, each of which is bounded in part along an arcuate line, the line of one portion being nearer the knife than that of the other portion, 20 the sole extending into contact with the blade, at the beginning of the splitting operation, past the first named portion and thereafter past the second named portion.

4. A machine for splitting the edge of a shoe sole along a line intermediate the upper and lower surfaces of the sole to form upper and lower lips, 25 comprising a frame, a shaft rotatably supported thereby, means for rotating said shaft, a cutting knife carried by the shaft, a stationary bed plate having an opening through which the shaft projects with the knife adjacent one surface of the bed plate, and means for permitting the adjustment of said shaft longitudinally to 30 shift the position of the knife relative to the bed plate.

5. A machine for splitting the edge of a shoe sole along a line intermediate the upper and lower surfaces of the sole to form upper and lower lips, 40 comprising a frame, a shaft rotatably supported thereby, means for rotating said shaft, a cutting knife carried by the shaft, a bed plate having an opening through which the shaft projects with the knife adjacent one surface of the bed plate, 45 a ring mounted in said bed plate defining the opening therein and surrounding and spaced from said shaft, and a guard plate carried by said frame, the knife being located between the ring and the guard plate whereby the sole to be split 50 is introduced between said ring and guard plate into contact with said knife.

6. A machine for splitting the edge of a shoe sole along a line intermediate the upper and lower surfaces of the sole to form upper and lower lips, comprising a frame, a shaft rotatably supported thereby, means for rotating said shaft, a cutting knife carried by the shaft, a bed plate having an opening through which the shaft projects with the knife adjacent one surface of the bed plate, 5 a ring mounted in said bed plate defining the opening therein and surrounding and spaced from 10 said shaft, and a guard plate carried by said frame and having an opening through which said shaft projects, the knife being located between the ring and the guard plate whereby the sole to be split is introduced between said ring and 15 said guard plate into contact with said knife.

7. A machine for splitting the edge of a shoe sole along a line intermediate the upper and lower surfaces of the sole to form upper and lower lips, 20 comprising a frame, a shaft rotatably supported thereby, means for rotating said shaft, a cutting knife carried by the shaft, a bed plate on which the sole rests having an opening through which the shaft projects with the knife adjacent one 25 surface of the bed plate, and a sleeve carried by said bed plate and lining the opening therein, said sleeve being spaced from said shaft and leading into a pocket in the frame whereby the fibers and dust made by the splitting operation pass 30 through the sleeve into the pocket.

8. A machine for splitting the edge of a shoe sole along a line intermediate the upper and lower surfaces of the sole to form upper and lower lips, 35 comprising a frame, a shaft rotatably supported thereby, means for rotating said shaft, a cutting knife carried by the shaft, a stationary bed plate having an opening through which the shaft projects with the knife adjacent one surface of the bed plate, 40 said frame having a pocket therein through which the shaft passes and into which the opening in the bed plate leads, and means for permitting the adjustment of said shaft longitudinally to shift the position of the knife relative to the bed plate said means including a collar surrounding that part of the shaft which 45 passes through the pocket.
